BATTER BOWL

Clarence M. Burroughs, Glendale, Calif., assignor to Burroughs Manufacturing Corporation, Los Angeles, Calif., a corporation of California

Application December 3, 1949, Serial No. 6,394

Term of patent 7 years

(Cl. D44—9)

To all whom it may concern:

Be it known that I, Clarence M. Burroughs, a citizen of the United States, residing at Glendale, in the county of Los Angeles and State of California, have invented a new, original, and ornamental Design for a Batter Bowl, of which the following is a specification, reference being had to the accompanying drawing, forming part thereof:

I claim:

The ornamental design for a batter bowl, as shown.

CLARENCE M. BURROUGHS.
